UNITED STATES PATENT OFFICE.

SAMUEL P. CRAFTS, OF HAMDEN, CONNECTICUT.

PORTABLE BRICK-KILN FURNACE.

SPECIFICATION forming part of Letters Patent No. 337,927, dated March 16, 1836.

Application filed December 18, 1835. Serial No. 186,087. (No model.)

To all whom it may concern:

Be it known that I, SAMUEL P. CRAFTS, a citizen of the United States, residing in the town of Hamden and State of Connecticut, have invented a new and useful Improved Portable Brick-Kiln Furnace, of which the following is a specification.

My invention relates to a portable brick-kiln furnace, and has for its object to provide a furnace for burning coal, which may be easily shifted from one kiln to another.

The invention consists in the novel construction and arrangement of the parts of the furnace, as hereinafter more fully described, and particularly pointed out in the claims.

In the accompanying drawings, Figure 1 represents my improved furnace and the method of its practical application to a brick-kiln. Fig. 2 is a view of one of the double transverse bars of the furnace base or frame, and Fig. 3 represents the mode of arranging and securing the grate-bars.

Referring to the drawings, A designates a brick-kiln built up in the usual and well-known manner and having the common transverse horizontal fire-arches B at the bottom. The sides of the kiln are faced with the ordinary non-conducting walls or casing, C, consisting of burned brick plastered over with clay. An aperture, l, for the passage of heat, is left in the casing at the mouth of each arch and lined with fire-brick to withstand the action of the heat. Above this aperture is a smaller one, e, which communicates with the peak or highest part of the arch.

In front of each fire-arch, and entirely exterior to the kiln, is a portable furnace consisting of a series of U-shaped arches, h, made of fire-clay and arranged upon an iron base or frame, which also supports the fire-grates i. The supporting-frame is composed of a pair of longitudinal bars, n, of cross-shaped section, and a series of transverse double bars, m, which are bolted to the bars n. The longitudinal bars are supported on brick walls d, and the grate rests on the transverse bars m. The grate is formed with two series of bars, which are arranged end to end, as shown in Fig. 3, and meet upon the middle transverse bar. The grate-bars are secured by means of projections r on their meeting ends, which set

into the space between the two parts of the middle double bar. The opposite ends of the grate-bars simply rest on the transverse bars, and are therefore free to expand and contract. 55 A furnace-front or door-plate, p, is arranged against and covers the front end of the arches B. It is bolted at the bottom corners to the ends of the bars n, and its upper part is braced by diagonal stays s, secured near the middle of the bars. The rear ends of the furnaces abut against the face of the kiln around the apertures or throats l, through which the heat passes freely into the arches. An air-tube, t, is placed over each furnace, with one 60 end resting on the furnace front and its opposite end inserted into the aperture e. The joint around the tube where it enters the wall is calked with clay and made air-tight. A loose brick wall, u, is laid up between the furnace-fronts, and the arches and tubes are buried under a bank of sand, earth, or loam, w, to prevent the radiation of heat. The sand contiguous to the furnace and around the tube 65 t becomes heated, and the tubes deliver a current of hot air into the peak of the arch for the purpose of facilitating and perfecting the combustion of the heated gases, and also giving a deeper red color to the bricks. The tube also serves as a peep-hole through which 70 the interior of the flue may be viewed.

Any kind of sand may be used for banking up the furnaces; but the fine striking-sand used in brick-making is the best for this purpose, and may in this manner be dried for use 75 without extra expense. These furnaces are placed on both sides of the kiln, one at each end of the arches B. The heat passes from the furnaces through the apertures into the arches, and thence between the bricks, and 80 the tubes t supply a sufficient quantity of heated air to oxidize the bricks, and thereby give them a deeper red color. It is evident that the arches may be formed rectangular or otherwise than U-shaped, and made in single 85 pieces, or in half-sections joined at the top. If desired, the supporting base or frame may be formed in one piece, having the transverse bars integral with the longitudinal bars.

The advantages of this furnace are that it is 90 inexpensive, easily moved from one kiln to another, and admits the use of coal in place of

wood, thereby lessening the expence and producing superior bricks.

I claim as new and desire to secure by Letters Patent—

- 5 1. A portable furnace for brick-kilns, consisting of a grate frame or base erected exterior to the kiln, a furnace-front or door-plate secured to the base, an arch of fire-clay mounted upon the grate frame or base and covered 10 with sand or other non-conducting material banked against the face of the kiln, and an air-tube arranged over the furnace within the covering, with one end inserted into the casing of the kiln and communicating with the peak 15 of the fire-arch for admitting heated air to the interior of the kiln, substantially as and for the purpose described.

2. In combination, the U-shaped arches *h*, longitudinal bars *n*, joined by transverse bars *m*, the grate-bars *i*, supported on the transverse bars, and the furnace-front or door-plate *P*, secured to the frame, all arranged and combined substantially in the manner and for the purpose described. 20

3. A furnace-grate composed of two series 25 of grate-bars arranged end to end and having projections *r* at their meeting ends which are adapted to fit between the sides of a double transverse bar, *m*, substantially as described.

SAMUEL P. CRAFTS.
